UNITED STATES PATENT OFFICE.

WEBB KIMBERLING, OF NORTON, VIRGINIA.

POLE-RAISING APPARATUS.

Application filed July 25, 1922. Serial No. 577,463.

To all whom it may concern:

Be it known that I, WEBB KIMBERLING, a citizen of the United States, residing at Norton, in the county of Wise and State of Virginia, have invented new and useful Improvements in Pole-Raising Apparatus, of which the following is a specification.

The object of my said invention is the provision of an apparatus simple in construction, light in weight and susceptible of easy operation whereby three men are enabled to raise poles such as telephone and power line poles and pull out old wooden poles with a minimum amount of effort.

The apparatus is also equipped to avert injury to the wall of a pole hole by guiding a pole into the hole, is adapted to be readily taken down, and is also adapted to be conveniently carried from one pole hole to another.

To the attainment of the foregoing, the invention consists in the improvement as hereinafter described and definitely claimed.

In the accompanying drawings, forming part of this specification:—

Figure 1 is a side elevation, partly in section and partly broken away showing my novel apparatus as arranged for the raising of a pole.

Figure 2 is a detail elevation taken at right angles to Figure 1.

Figure 3 is an enlarged detail side elevation illustrative of the mounting of the drum of the apparatus.

Figure 4 is an enlarged detail of the same taken at right angles to Figure 3.

Figure 5 is an enlarged detail section taken in the plane indicated by the line 5—5 of Figure 4, looking toward the left.

Figure 6 is an enlarged fragmentary section showing the upper portion of the apparatus and the cap over sheave.

Similar numerals of reference designate corresponding parts in all of the views of the drawings.

Among other elements my novel apparatus comprises a main pole, the said main pole being made up of lower and upper timbers 1 and 2, connected together through the medium of strap irons 3 and bolts 4, the said bolts 4 being passed through metallic bearings 5 in the timbers. The main pole is removable—i. e., is separated from the remainder of the apparatus when the apparatus is to be carried from one pole hole to the next.

My invention contemplates the raising of the main pole by one man manipulating the crank handle 6 while two other men steady the pole with spike poles or hand lines (not illustrated).

When the main pole is in upright position it is braced through the medium of two adjustable braces, and a wooden brace 7 is employed for steadyng and raising the main pole and the apparatus as a whole. One of the adjustable braces is shown in Figure 1 and designated by 8, and I would have it understood that the other adjustable brace 8 at the opposite side of the main pole is similar to the one shown in Figure 1. The brace 8 of Figure 1 is made up of an upper section 9 of gas pipe, a lower section 10 preferably of iron pipe and pointed at its lower end 11, a metallic collar 12 and set screws 13. Manifestly the said brace 8 is adapted to be readily increased and diminished in length and the section 10 is adapted to be fixed to the section 9 in a strong manner by the screws 13 which extend through the collar 12 and the section 8 and are set against the section 10.

The adjustable capacity of the braces 8 adapts the apparatus for use on various surfaces and hence the apparatus may be used to advantage on hill sides and on level tracts.

In order to take down the timber or main pole member 2, the uppermost bolt 4 is removed, and the bolt 4 below the uppermost one is utilized as a pivot for the upper member 2. When short poles are to be raised the lower member or timber 1 of the main pole need not be employed.

Connected by a bolt 14 to the lower member 1 of the main pole is a U-shaped member 15, and appropriately connected at 16 to the said member 15 is a pole guide 17, of sheet metal or other appropriate material. The said guide 17 being adapted to depend into a pole hole designated by 18 in Figure 1 and to rest adjacent to one wall 19 of the pole hole so as to guide the lower end of the pole to be raised, designated by 20, into the hole and at the same time avert caving in or injury to the said side of the hole 18 incident to the raising of the pole. By removing the bolt or bolts 14 the guide 17 and its appurtenances can be easily disassociated from the member 1 of the main pole.

The braces 8 are by preference pivotally connected to the member 2 of the main pole, as designated by 21, and the wood brace 7 is provided at its upper end with one or more

straps 22 of iron on which are hooks 23 to engage studs 24 provided on the sides of the member 2, Figures 1 and 2. Manifestly the wood brace 7 is adapted to be quickly and easily engaged with and disengaged from the main pole member 2.

At 24 the device is provided with metallic handles so that the device or apparatus can be conveniently carried.

At the top of the main pole member 2 a sheave 25 is provided, the said sheave 25 being mounted between the extended portions of strap irons 26, fixed at 27 to the member 2, and the said sheave being disposed under and protected by a cap 28 which is mounted on the strap irons 26 as shown in Figures 1, 2 and 6.

A flexible steel cable 30 is employed as a part of the apparatus and is designed to be tied around a pole 20, as indicated by 31 in Figure 1. The said cable is passed over the sheave 25, and is then carried downwardly and adapted to be wound on a drum 32, Figures 2, 4 and 5. The said drum 32 is appropriately fixed to a shaft 33 on which are also fixed brake disks 34; and it will also be noted that the said shaft 33 is journaled in bearings 35 and is equipped at 36 with a large spur gear, the said spur gear being associated with a gravitational detent 37 for preventing retrograde rotation thereof. The bearings 35 are carried by upright frame members 40 as are also lower bearings 41 and the bracket arm 42 to which the before mentioned detent 37 is pivoted. In the lower bearings 41 a shaft 43 is journaled, and this shaft 43 is adapted at one end for the application of the before mentioned crank 6, and is equipped with a spur gear 44, intermeshed with the before mentioned large gear 36. Blocks 45 are interposed between the bearings alluded to and the upright frame members 40, and the bearings, blocks 45 and the upright members 40 are fixedly connected together through the medium of bolts 50 on which are appropriate nuts 51. It will also be noticed that the uprights 40 are maintained in proper relation to the lower main pole member 1 through the medium of metallic straps 60, said straps 60 being fixed at the lower and upper ends of the members 40, and being arranged at opposite side of the main pole member 1, and provided with bolts 61 at opposite side of said main pole member.

Carried by the blocks 45 is a rock shaft 70 to which is fixed a lever 71. Also fixed to the rock shaft 70 are arms 72, the said arms 72 being connected to certain ends of brake bands 73; the other ends of which are connected to studs 74 carried on the blocks 45. It will be readily manifest that incident to the raising of a pole by the turning of the crank 6, the operator who

turns the crank is enabled at any time to conveniently brace on the angular lever 71 and thereby apply the brake band 73 to the disks 34 so as to preclude a fall of the pole that is being raised.

In the present and preferred embodiment of my invention the upright members 40 are appropriately fixed to a base 40*, Figures 1 and 2, the said base 40* being provided with spikes 41*, designed to be embedded in the ground after the manner illustrated with a view to precluding casual movement of the lower end of the apparatus when the same is in use.

In addition to the practical advantages ascribed to my novel apparatus it will be noted that the apparatus is simple and inexpensive in construction and is well adapted to withstand the rough usage to which apparatus of corresponding character is ordinarily subjected.

In virtue of its construction my novel apparatus is also adapted to be used to advantage for placing heavy load on trucks and wagons.

I have entered into a detailed description of the construction and relative arrangement of the parts embraced in the present and preferred embodiment of my invention in order to impart a full, clear and exact understanding of the said embodiment. I do not desire, however, to be understood as confining myself to the specific construction and relative arrangement of parts inasmuch as in the future practice of the invention various changes and modifications may be made such as fall within the scope of my invention as defined in my appended claims.

Having described my invention, what I claim and desire to secure by Letters-Patent, is:—

1. A raising apparatus comprising a frame, a main pole socketed in and removably associated with the frame, a sheave carried at the upper end of the main pole, means for bracing said pole, said means being adjustable and detachably associated with the pole, a cable passed over the sheave and adapted to be attached to the device to be raised, and winding mechanism carried by the frame and adapted to take up the cable; the said frame comprising spaced uprights, a base fixed to the lower end of said uprights and having spikes, and straps connecting the lower and upper portions of the uprights and disposed at opposite sides of the said main pole.

2. A raising apparatus comprising a frame, a main pole socketed in and removably associated with the frame, a sheave carried at the upper end of the main pole, means for bracing said pole, said means being adjustable and detachably associated with the pole, a cable passed over the sheave

and adapted to be attached to the device to be raised, and winding mechanism carried by the frame and adapted to take up the cable; the said main pole comprising a lower member, an upper member, side straps bolted to the lower member, a lower bolt extending through and connecting the side straps and the upper member, and an upper bolt removably arranged in and connecting the side straps and the upper member **10** whereby when the upper bolt is removed the upper member is adapted to be swung on the lower member.

In testimony whereof, I affix my signature.

WEBB KIMBERLING.
